(57) **CLAIM**

The ornamental design for a case for an E-reader device with viewing stand and hand strap, as shown and described.

DESCRIPTION

FIG. 1 is a left side view of a case for an E-reader device with viewing stand and hand strap, showing my new design;

FIG. 2 is a front view thereof;

FIG. 3 is a right side view thereof;

FIG. 4 is a rear view thereof;

FIG. 5 is a top side view shown folded into a configuration of

use; and,

FIG. 6 is a front perspective view thereof.

The broken lines represent stitching and form part of the

claim.
